UNITED STATES PATENT OFFICE.

JOHN TASEFF, OF LOS ANGELES, CALIFORNIA.

FACING BLOCK FOR FRAME BUILDINGS.

Application filed January 24, 1925. Serial No. 4,433.

To all whom it may concern:

Be it known that I, JOHN TASEFF, a citizen of the United States, residing at Los Angeles, in the county of Los Angeles, State 5 of California, have invented new and useful Improvements in Facing Blocks for Frame Buildings, of which the following is a specification.

My invention relates to wall construction 10 and more particularly to facing-blocks for walls of frame buildings and means for attaching them to such walls.

One object of my invention is to provide a facing-block preferably made of cement or 15 concrete in imitation of stone or marble, for covering the outer walls of frame houses and like structures for the purpose of rendering them practically fireproof and also for the purpose of giving them the appearance 20 of brick or stone buildings.

Another object is to provide a facing-block of the character described which will be comparatively inexpensive to use and which may be applied to walls readily and 25 quickly by unskilled workmen.

Other objects and advantages will appear hereinafter and while I show herewith and will describe a preferred form of construction, I desire it to be understood that I do not limit my invention to such preferred 30 form but that various changes and adaptations may be made therein without departing from the spirit of my invention as hereinafter claimed.

Referring to the drawings which accompany 35 this specification and form a part thereof:

Fig. 1 is a view in perspective of one form 40 of my facing-block showing the back side of a whole block and a fragment of an adjacent second block and illustrating the manner of joining the ends of adjacent blocks in the same course in a wall.

Fig. 2 is a vertical sectional view of a wall 45 to which facing-blocks of the form shown in Fig. 1 are applied, illustrating one method of attaching them thereto.

Fig. 3 is a view in perspective of a second 50 form of facing-block.

Fig. 4 is a fragmentary view of a wall block which is equipped with facing-blocks 55 of the second form.

Fig. 5 is a view in perspective of a bracket 60 adapted for use in attaching the second form of block to a wall, as illustrated in Fig. 4.

Fig. 6 is a vertical sectional view of a wall 65

faced with blocks of the second form and showing two methods of attaching them thereto.

Fig. 7 is a fragmentary view in perspective 70 of the wall construction shown in Fig. 6, more clearly illustrating details of the means for securing the blocks to the wall.

Fig. 8 is a view in perspective of a third 75 form of facing block showing the back side thereof and means for attaching it to a wall.

The different forms of blocks shown all 80 have plane faces which may be finished to resemble brick, stone, marble, or granite. They may be made of any desired size and 70 of any desired proportions as to length and width, but must be made relatively thin, except for special purposes as will be seen.

The form of block shown in Figs. 1 and 2 85 consists of a rectangular slab 10 having woven wire 11 or similar reinforcement imbedded therein, with longitudinal ribs 12 on its back side offset from its edges to such an extent as to form angles 13 therealong. Cross ribs 14, at a spaced distance from the 90 ends of the block, extend between ribs 12 at right angles thereto. The inner sides 15 of ribs 12 are beveled from the back face of slab 10 outward and relatively thick and stiff wires or rods 16 imbedded therein extend through cross ribs 14 and project beyond ribs 12 at one end to form locking pins 17. A relatively thin and soft wire is imbedded 95 in the block near the opposite end from that of the locking pins and the ends of said thin wire are brought out through ribs 12 to form tie wires 18.

The block thus formed is mounted as shown in Fig. 2. Vertical strips 19, uniformly spaced, are nailed to the sheathing 95 20 of the house wall and stub nails 21 are driven into the sheathing so that their projecting heads are in position to be engaged by tie wires 18. The blocks are applied to the wall in courses with some kind of mortar between them in the usual way, except that each block is secured at one end to the stub nails 21 by the tie wires 18 and the locking pins 17 of each succeeding block are inserted into the inner angles 22, formed by ribs 12 and slab 10, at the tie wire end of the preceding block. One end of each block being thus locked into the preceding block and having its other end tied to the stub nails. each individual block is securely 105 held in place.

Straight slabs 23 of the same material as

the facing-blocks and of equal length, but of any desired width, may be filled in between adjacent courses of blocks, their edges being adapted to engage with angles 13 of 5 the facing blocks, as shown in Fig. 2, so that they are securely held in place by the facing blocks.

The form of block shown in Figs. 3 and 4 consists of a straight rectangular slab 24 10 of reinforced cement or concrete, having equally spaced holes 25 formed in each end thereof. These may be attached to the walls of a building in various ways. One method is to provide brackets 26 of the form shown 15 in Fig. 5, made of pieces of sheet metal, with a perforated lug 27 and oppositely extending perforated legs 28 adapted to be nailed to the wall sheathing so that said lug projects in a vertical plane from the side thereof. Pairs of these brackets are placed in 20 vertical alignment with each other at points between the ends of adjacent blocks in a course, and the blocks are held in place by pins 29 made of pieces of stiff wire which 25 are inserted through the perforations in lugs 27 and into holes 25 of one end of a block, the next block in the course being added by bringing holes 25 in one of its ends into 30 engagement with the projecting ends of said pins, and so on throughout the course. With this arrangement it is evident that vertical strips 19 and stub nails 21 are not necessary.

Another method of attaching this form of block is to provide vertical strips 19 and stub 35 nails 21, as for the first form, and to use tie wires wrapped around pins 29 between the ends of adjacent blocks and around the stub nails. Brackets 26 are not necessary when this method is employed.

40 Other modifications of this block and mounting means for same are shown in Figs. 6 and 7. The reinforcing material 30 may be extended so as to project from the upper and lower edges of the block and may be 45 bent into the form of a hook 31 along its upper edge and a downwardly projecting flange 32 along its lower edge. Or relatively stiff pieces of wire may be embedded in the block transversely thereof near its ends with 50 their ends projecting from its upper and lower edges. The upper ends of said projecting wires are then bent into hooks 33 and the lower ends into downwardly projecting and inwardly curved retaining pins 34.

55 When either of the latter forms is used, horizontal hanging strips 35, preferably of channel iron, are fixed to the side of the building across vertical strips 19 adjacent the upper edge of each course of blocks and 60 spacing strips 36 are similarly fixed across said vertical strips adjacent the lower edge of each course of blocks. The blocks are then attached to the building by inserting flange 32, or pins 34, behind strip 35 of the 65 adjacent lower course of blocks and by

bringing hooks 31 or 33 into engagement with strip 35 of the course which is being applied.

Special forms of blocks may be placed 70 over window and door openings or in certain positions for ornamental purposes and special means of attaching them may be provided. One such form is shown at 37, each block being attached to the building 75 by means of a bolt 38 having its head end imbedded in the block and its threaded end projecting from the back side thereof so that it may extend through a hole in the wall sheathing and be secured thereto by a nut 39 and washer 40.

80 The third form of facing block, shown in Fig. 8, consists of a rectangular slab 41, similar to that of the first and second forms, having transverse ribs 42 on its back side near its ends, said ribs having equally spaced 85 holes 43 near their ends through which relatively thin soft wires 44 extend, so that their projecting ends 45 may serve as tie wires. This form of block may be attached to walls provided with vertical strips 19 90 and hanging strips 35 by using tie wires 45 to secure them to the latter strips. Or both vertical and horizontal strips may be dispensed with and stub nails 21 only may be used, in connection with tie wires 45, as 95 fastening means.

It will be understood that in applying blocks of the second or third form to a wall some kind of mortar is used between them as with the first form, whatever means may 100 be employed for attaching them to the wall.

Having thus illustrated and described my invention, I claim:

1. A moulded facing-block for frame buildings comprising a reinforced rectangular slab, ribs formed on the back side of said slab, locking pins fixed in said ribs so as to engage with adjacent blocks in the same course when being applied to a wall, and tie wires fixed in said ribs, said tie wires being adapted to fasten said blocks to supplementary attaching means fixed to the side of a wall.

105 2. A moulded facing-block for frame buildings comprising a reinforced rectangular slab, longitudinal ribs formed on the back side of said slab adjacent the edges thereof, transverse ribs between said longitudinal ribs at a spaced distance from the ends of said slab, locking pins fixed in said transverse ribs so as to project beyond one end of said slab, and tie wires fixed in said longitudinal ribs at the opposite end of said slab from said locking pins, said locking pins being adapted to engage adjacent blocks in the same course when applied to a wall and said tie wires being adapted to fasten said blocks to supplementary attaching means fixed to the side of a wall.

110 120 125 JOHN TASEFF.
